UNITED STATES PATENT OFFICE

JOHN H. WHITWELL, OF PHILADELPHIA, PENNSYLVANIA

DESIGN FOR WALL PAPER

Application filed March 15, 1929. Serial No. 30,487. Term of patent 3½ years.

To all whom it may concern:

Be it known that I, JOHN H. WHITWELL, a citizen of the United States, residing at Philadelphia, in the county of Philadelphia and State of Pennsylvania, have invented a new, original, and ornamental Design for Wall Paper, of which the following is a specification, reference being had to the accompanying drawing, forming a part thereof.

The figure shows my new design for wallpaper, a complete repeatable unit being included within the indicating lines on the drawing.

I claim:—

The ornamental design for wallpaper substantially as shown and described.

JOHN H. WHITWELL.
